CLOTHESLINE RING

Trumon Dossey, Aruba, Dutch West Indies

Application November 21, 1933, Serial No. 699,054

1 Claim. (Cl. 24—139)

The invention relates to a clothesline ring and more especially to a clothespin or ring.

The primary object of the invention is the provision of an article of this character wherein clothes or other articles of fabric may be conveniently fastened upon a line so as to prevent any possibility of the accidental removal from the line, the ring or pin being of novel construction so as to permit the convenient fastening 10 of the same in place with dispatch when securing clothing or like articles upon a clothesline.

Another object of the invention is the provision of a ring or pin of this character, wherein the same is in the form of a spring hook or loop with the ends overlapping and reversely curled so that the application of the ring or pin to a clothesline when fastening clothes thereon or like articles can be carried forth with dispatch and without inconvenience to the user.

A further object of the invention is the provision of a pin or ring of this character which is extremely simple in construction, thoroughly reliable and efficient in its purpose, strong, durable, easily and conveniently manipulated for 25 the fastening or removing of clothes to and from a line, and inexpensive to manufacture.

With these and other objects in view, the invention consists in the features of construction, combination and arrangement of parts as will 30 be hereinafter more fully described in detail, illustrated in the accompanying drawing, which discloses the preferred embodiment of the invention, and pointed out in the claim hereunto appended.

In the accompanying drawing:

Figure 1 is a perspective view of the ring or pin constructed in accordance with the invention.

Figure 2 is a side elevation showing the position of the ring or pin for the initial introduction to the line when clothing is hung thereon.

Figure 3 is a view similar to Figure 2 showing the ring or pin engaged with the clothing and the line.

Figure 4 is a vertical sectional view through the clothing and line with the ring or pin attached.

Similar reference characters indicate corresponding parts throughout the several views in the drawing.

Referring to the drawing in detail, A designates generally a portion of a clothesline and B a portion of an article of clothing hung thereon, while C is the ring or pin constituting the present invention and hereinafter fully described.

The ring or pin C comprises a single length of inherently resilient wire bent on itself to provide a circular portion 5 and reversely extending end portions 6, these being arranged at opposite sides of the circular portion 5 and having the outwardly, downwardly and inwardly curled terminals 7 or eye tips, the end portions 6 being 10 normally in contact with the circular portion 5 and overlapping the latter for substantially one-half of its diameter or circumference.

In the use of the ring or pin either terminal or eye tip 7 is disposed in side contact with the line A or the article B hung thereon and by 20 downward pressure and a rolling motion the portions 6 will spring apart to accommodate therebetween the line A and article B hung thereon so as to assume the position as shown in Figures 25 3 and 4, thus detachably fastening the article B upon the line A. The terminals or eye tips 7 are disposed in a lateral outward direction to lie in substantially the same plane of the pin proper 30 in contradistinction to being bent at right angles to such plane, so that when the clothespin is engaged upon a line having a piece of material hung thereon, the terminals or eye tips 7 will underlie the rope or clothesline for a positive 35 latching of the piece of material thereon without liability of the said piece of material becoming loose when attacked by wind.

What is claimed is:

A ring or pin of the kind described, comprising a single convolution formed from a length of resilient wire, the free ends of the wire being outwardly and inwardly curled at opposite sides of the convolution and disposed to project entirely without the said convolution to be exposed to their full extent beyond the convolution and at 45 diametrically opposite points with respect thereto.

TRUMON DOSSEY.
